UNITED STATES PATENT OFFICE.

CLIFFORD A. JARVIS, OF RUSHVILLE, INDIANA.

SELF-REELING HOSE REEL.

Application filed September 21, 1923. Serial No. 664,107.

To all whom it may concern:

Be it known that I, CLIFFORD A. JARVIS, a citizen of the United States, residing at Rushville, in the county of Rush and State 5 of Indiana, have invented new and useful Improvements in Self-Reeling Hose Reels, of which the following is a specification.

The principal object of this invention is to provide a reel upon which flexible hose 10 such as is used for lawn, garden, and hot-house sprinkling, is wound when the sprinkling operations are not in progress, and from which it is easily unreeled either fully or partially and used while connected with 15 the water supply, and which is automatically re-reeled as soon as released by the operator, in a manner to drain the hose and also in a manner to preserve it from injury by breaking, kinking, or abrasion, as 20 frequently happens when reeled by hand, or when not reeled at all, as is generally the situation.

A further object is to provide a swivel joint in a water conduit from the hose to 25 the hydrant, passing through the axis of rotation of the reel drum, which swivel joint will be water tight without interfering with the easy rotation of the drum.

The object, also, is to provide a spring 30 means which is wound up by the unreeling of the hose and which exerts its stored power for re-reeling it without interfering with the easy and practical operation of the device for the purpose intended.

I accomplish the above, and other objects 35 which will hereinafter appear, by the mechanism illustrated in the accompanying drawing, in which—

Fig. 1, is a perspective view of a hose reel 40 for domestic use, embodying my improvements, and Fig. 2, is a longitudinal section through the axis of the drum, on the line 2—2 of Fig. 1.

Like characters of reference indicate 45 like parts in the two views of the drawing.

The drum 3, upon which the hose 4 is 50 reeled, is rotatably supported on a carriage comprising a pair of frame-bars 5 and 6, having turned-down ends that support an axle 7 on which wheels 8 are mounted for easy transportation of the whole device. A cross bar 9 spaces and strengthens the 55 turned-down ends of the frame-bars. The opposite ends of the frame-bars are rigidly attached to respective legs 10, 10, and the leg-bars are continued upwardly to support

a connecting handle-bar 11. A cross bar 12 connects the handle-bars near their junction with the frame-bars, and above the cross bar 12, is a friction roller 13, across which the 60 hose is drawn when reeled and unreeled. One of the handle-bars has a spring clamp 14 to hold and retain the hose nozzle whenever desired.

The frame-bars, 5 and 6, have suitable 65 standards 15, with openings in which shafts of drum 3 are supported. The drum 3 is preferably hollow sheet metal, the ends of which are soldered or otherwise rigidly fastened to the respective circular metal disks 70 16 and 17 having central openings in which the respective ends of a smaller pipe 18 fits, and are soldered or otherwise rigidly fastened. Filling that end of pipe 18 which is 75 next to the disk 17, is a metal cylinder 19, having a central bore extending only part way through the length of the cylinder, from its outer end, as shown in Fig. 2. This bore is expanded near its outer end to fit a tapering swivel plug 20. The inner and 80 outer ends of plug 20 are cylindrical for bearing in correspondingly cylindrical portions of the bore in cylinder 19 and the plug has a central longitudinal hole in which a pipe 21 is rigidly fitted by driving it in 85 tightly, or in any suitable manner.

A standard hose connection 22 is screwed 90 into a threaded hole made through the pipe 18 and through the adjacent wall of the cylinder 19 into the bore of said cylinder and provides a discharge from the cylinder 19, through said connection 22.

The outer end of cylinder 19 projects 95 through and beyond the disk 17 and is externally screw threaded to receive a cap 23. 95 A leather washer 24 makes contact between the cap and end of plug 20, whereby the tapering plug is forced into its seat to make a water tight joint without causing friction enough to interfere with the free rotation 100 of the plug in its seat when the reel drum is rotated.

On the outer end of pipe 21 is an elbow 105 44 having a standard hose connection 25 to which a hose 26, connected with a hydrant 27, is attached. The drum 3 is cut away at 28 to provide a hand-hole for the attachment and removal of the hose 4.

Seated in a fixed manner in that end of 110 pipe 18 which is next to disk 16, is a bushing 29, having a central bore in which a shaft 30 is rotatably journaled. This shaft has

a transverse slot which receives the inner end of a flat, coiled, spring 31, the outer end of which spring is secured by bolts 32 to the rim 33 of a housing.

5 The rim has a flange through which screws 34 removably secure it to the disk 16.

To the side 35 of the housing a plate 36, of less diameter than said side, is riveted, and integral with plate 36 is an outside boss 10 37 having a central bore in which shaft 30 is additionally journaled.

A cotter-pin 38 passes through the shaft and contacts boss 37 to keep the shaft from moving lengthwise and binding spring 31, 15 against the end of the drum. A plate 39 is preferably introduced in the housing between the spring and end of drum to hold the spring in uniform central position, and an outside plate 40 bears on the boss 37 and 20 is dished around the plate 36 to strengthen and finish the housing.

The outer end of shaft 30 is mounted in a fixed manner in adjacent standard 15 on frame-bar 5.

25 The outer end of the spring 31 being fastened at 32 to the housing which rotates with the flange 16 and drum 3 when the hose is being unreeled, and the other end of the spring being fastened to the shaft 30 which is stationary at all times, the spring is wound up; but when the operator releases the hose the spring 31 unwinds and rotates the drum 3, in a direction to rewind the 30 hose on it.

30 The housing may be removed, for repairs to the spring or otherwise, by removing screws 34, and the cotter-pin 38.

Having thus fully described my invention, what I claim as new and wish to secure by 35 Letters Patent, is—

1. In a hose reel, a pair of parallel disks, a cylindrical drum uniting the disks, a pipe within the drum also uniting the disks, a plug in one end of the pipe having a bore 40 in the axis of rotation of the drum, a fixed

shaft in the bore upon which that end of the drum rotates, a spring coiled around the shaft and having its inner end fastened to the shaft, means for fastening the other end of the spring to the drum, a cylinder in the other end of the pipe having a bore in the axis of the drum, a lateral hose connection connecting with the inner end of the bore, said bore being expanded outwardly near the outer end which end projects through the adjacent disk and is screw-threaded, a correspondingly tapering plug seated in the expanded bore of the cylinder, a cap screwing on the threaded end of the cylinder and regulating the pressure of the plug in its seat, a gasket between the cap and plug, and a pipe connected with a water supply and the plug and discharging longitudinally through the plug.

2. In a hose reel, a relatively fixed support, a shaft rigidly mounted on the support, a drum having one end journaled on the shaft, a disk at that end of the drum said disk having a rim, a coiled spring fastened at one end to the shaft and at the other end to the rim, a boss on the shaft, a plate between the drum and spring to center the spring and an outside plate bearing on the boss to strengthen and finish the housing of the spring.

3. In a hose reel, a relatively fixed support, a shaft removably mounted on the support, a drum mounted at one end on the shaft said drum having a disk, a rim, means for removably securing the rim to the disk, a coiled spring fastened at one end to the shaft and the other to the rim, a boss removably mounted on the shaft, means for removably securing the boss to the shaft, and a plate bearing on the boss to strengthen and finish the housing of the spring.

Signed at Indianapolis, Indiana, this the 12th day of September, 1923.

CLIFFORD A. JARVIS.
